UNITED STATES PATENT OFFICE.

EDWARD A. LARSON, OF CHICAGO, ILLINOIS, ASSIGNOR TO STEWART-WARNER SPEEDOMETER CORPORATION, OF CHICAGO, ILLINOIS, A CORPORATION OF VIRGINIA.

LIQUID-FEEDING DEVICE.

1,153,696.

Specification of Letters Patent. Patented Sept. 14, 1915.

Application filed March 12, 1915. Serial No. 14,027.

To all whom it may concern:

Be it known that I, EDWARD A. LARSON, a citizen of the United States, residing at Chicago, in the county of Cook and State 5 of Illinois, have invented new and useful Improvements in Liquid-Feeding Devices, of which the following is a specification, reference being had to the accompanying drawings, forming a part thereof.

10 This invention relates to a liquid feeding system which involves drawing the liquid from a low level supply to an elevated receptacle by producing a partial vacuum in the receptacle, and then periodically permitting the liquid thus elevated to flow by gravity to the point of use.

15 The invention is directed to simplifying the mechanism in the elevated receptacle without sacrificing the certainty of the operation, and consists in the features and elements described hereinafter and shown in the drawings as indicated by the claims.

20 In the drawings: Figure 1 is a vertical section of a receptacle and the mechanism contained therein embodying this invention. Fig. 2 is a similar section illustrating a modified form of the invention.

25 This device is especially designed for use on motor vehicles employing liquid fuel, being adapted for transferring the fuel from a low-level tank carried in any convenient position as under the vehicle at the rear, to the carbureter associated with the explosive engine, and generally located above the level 30 of the supply tank.

35 The receptacle which is the subject of this invention is positioned somewhat above the carbureter float chamber, so that the fuel lifted by it from the low-level tank may 40 flow from it by gravity into the carbureter chamber. As illustrated in the drawings, the receptacle comprises an outer chamber, 1, and an inner chamber, 2, each being a flanged cup, and the latter being suspended 45 within the former with its flange, 2^a, secured in position above the flange, 1^a, of the outer vessel. The cup closure consists of a cover, 3, having a flange, 3^a, with a skirt portion, 3^b, overhanging the flanges, 1^a and 50 2^a, of both vessels. These elements are secured together by means of screws, 4, passing through the flange, 1^a, into tapped holes in a ring, 5, and screws, 6, passing through the flanges, 3^a and 2^a, into other tapped 55 holes in the same ring, 5. Preferably, pack-

ing rings, 7, are interposed at both faces of the flange, 2^a, to insure that the interior of the vessel, 2, shall be air-tight, but this precaution is not deemed necessary in the case of the vessel, 1, which in fact is provided 60 with a constantly open atmospheric vent formed by crimping the flange, 1^a, at 1^b, thus forming a passage which communicates with the narrow annular space, 1^c, between the side walls of the vessel, 1 and 2, and 65 leads to the chamber formed by the vessel, 1. The lower end of the vessel, 1, is fitted with a large threaded flange or neck, 1^d, which may be screwed directly on to the float chamber of a carbureter or to a conduit 70 leading to the same.

75 From the low-level supply tank, not shown, a pipe leads into the cover, 3, by way of a fitting, 8. Through a rather small opening at 9, the receptacle is intended to be 80 kept in constant communication with a source of suction, such as the intake manifold of the engine or an auxiliary exhaust pump, as may be preferred. As a partial 85 vacuum is thus produced in the receptacle, 2, the liquid from the low-level supply tank is caused to flow into the receptacle, and in so doing tends to raise the float, 10, which is mounted therein.

90 As illustrated in Fig. 1, the stem, 10^a, of the float, 10, is connected pivotally to a lever, 11, fulcrumed at 12, on the cover 3, and carrying a flat spring, 13, secured to its outer or free end by a screw, 14. The opposite and free end of the spring 13, which is quite 95 close to the fulcrum, 12, supports a valve, 15, which controls the air vent opening, 16, through which atmospheric pressure is periodically restored in the receptacle, 2. It will be understood that by reason of the 100 suction within the receptacle, 2, the air valve 15, will be held quite firmly on its seat, so that as the liquid level in the receptacle, 2, rises, and the float, 10, is thus elevated, the spring, 13, will be slightly deflected toward the lever, 11, and the rising of the float, 10, may be retarded so that the float will not stand quite up to its normal level in the liquid, but will accumulate 105 buoyant force until the energy thus stored up in the float and in the spring, 13, is sufficient to snap the valve, 15, open against the atmospheric pressure acting upon it. The spring, 13, having previously been compressed toward the lever, 11, and being now 110

released, will obviously support the valve, 15, clear above the aperture which it controls, thus giving free access of atmosphere to the interior of the vessel, 2; and since the atmospheric opening, 16, is of considerably greater area than the suction aperture, 9, the effect of the suction will be completely neutralized as long as the valve, 15, remains open, even though the aperture, 9, is not closed. Upon the admission of atmospheric pressure to the vessel, 2, the liquid accumulated therein will flow by gravity into or through the lower chamber formed by the vessel, 1, which is constantly under atmospheric pressure, automatically opening the flap valve, 17, provided for this purpose. When reduced pressure is again restored in the vessel, 2, the valve, 17, will be held shut thereby in an obvious manner.

As a modification of the structure above described, Fig. 2 illustrates the float, 10, as loosely mounted upon its stem, 18, which is also the stem of the air valve, 19, controlling admission of the atmospheric pressure to the interior of the vessel, 2. At its lowest position the float, 10, hangs upon a collar, 18^a, on the stem, 18, thus holding the valve, 19, closed, but as the float, 10, begins to rise with an increase of liquid level in the receptacle, 2, it supports the valve, 19, yieldingly upon a very light spring, 20, coiled about the stem, 18, and engaging a stop collar, 21, secured thereto just below the atmospheric opening. The collar, 21, is notched so that when sufficient upward pressure has been accumulated in the form of buoyant force acting on the float, and energy stored in the spring by compression thereof, the valve, 19, will be snapped off its seat and its upward movement will be limited by engagement of the stop, 21, with the underside of the portion of the cover, 3, in which the atmospheric opening is formed, but the stop, 21, will not operate to close the opening. It will be noted, that in this form also the atmospheric opening controlled by the valve, 19, is quite large relatively to the suction aperture, 9, so that considerable pressure must be accumulated by the float to overcome the effect of the suction on the valve, 19, but so that when the valve, 19, is open the large capacity of the atmospheric opening will entirely neutralize the effect of the suction at the aperture, 9. In former devices for this purpose the more successful construction has involved a mechanism for simultaneously opening the atmospheric vent and closing the suction aperture, and for simultaneously reversing this arrangement, but such mechanism necessarily involves considerable complication and expense to insure proper adjustment of the two valves relatively to each other so that their operation may be properly simultaneous.

It may be observed that the above described construction, in which the suction connection opening is comparatively small and remains constantly open, might perhaps be operated simply by a float connected directly to the stem of the atmospheric vent valve. But if the float were large enough to easily overcome the pressure on the atmospheric valve, it would tend to raise it only just enough at first to neutralize the effect of the suction at 9, without however actually introducing atmospheric pressure into the receptacle, 2. This would prevent, or at least render very uncertain, the release of the liquid by way of the valve, 17, and the atmospheric valve would simply tend to vacillate between slightly open and closed position, rendering the entire operation of the device very uncertain and unsatisfactory.

It has been found that if the float is so designed that its rise in the liquid will be substantially retarded by the atmospheric pressure on the valve, thus rendering the accumulation of buoyant force in the float equivalent to the accumulation of energy in the spring shown, the necessary dimensions of the float and the receptacle would be awkward and inconvenient for the purpose. It is, therefore, deemed much preferable to make the float of any convenient dimensions, such as those shown, and sufficiently large to furnish an excess of power for opening the valve, and then to supplement its action with the action of a light spring, which will yield as the float rises and until the valve snaps open, but which will be stiff enough to support the valve at some distance above the aperture. In this way the operation is rendered positive and uniform.

I claim:

1. A device for the purpose indicated, comprising a chamber adapted for connection with a low-level liquid supply and with a source of suction, the suction connection comprising a constantly open orifice of comparatively small capacity, said chamber having an atmospheric air vent of large capacity, a valve controlling said vent, a float in the chamber, and a yielding connection between said valve and said float.

2. A device for the purpose indicated, comprising a chamber adapted for connection with a low-level liquid supply and with a source of suction, the suction connection comprising a constantly open orifice of comparatively small capacity, said chamber having an atmospheric vent of large capacity, a valve controlling said vent, a float in the chamber, and yielding means positioned to transmit pressure from the float to the valve in direction for opening the latter.

3. A device for the purpose indicated, comprising a chamber adapted for connection with a low-level liquid supply and with a source of suction, the suction connection

comprising a constantly open orifice of comparatively small capacity, said chamber having an atmospheric air vent of large capacity, a valve controlling said vent, a lever 5 fulcrumed in the chamber, said valve being connected to said lever near its fulcrum, and a float in the chamber connected to the lever at a point farther from its fulcrum.

4. A device for the purpose indicated, 10 comprising a chamber adapted for connection with a low-level liquid supply and with a source of suction, the suction connection comprising a constantly open orifice of comparatively small capacity, said chamber having an atmospheric air vent of large capacity, a valve controlling said vent, a lever fulcrumed in the chamber, means yieldingly connecting said lever to said valve near its fulcrum, and a float in the chamber connected to the lever at a point farther from its fulcrum.

5. A device for the purpose indicated, comprising two flanged vessels, one of which is suspended within the other, a ring inter-

posed between said flanges having a series 25 of threaded apertures, screws passing through the upper flange into certain of said apertures in the ring, and other screws passing through the lower flange into the other apertures of said ring securing the two vessels together.

6. A device for the purpose indicated, comprising two flanged vessels, one of which is suspended within the other, with its flange overhanging the flange of the other, an annular space being formed between the cylindrical walls of the two vessels, and the flange of the outer vessel being crimped away from the flange of the inner vessel to afford communication between said annular space and 35 the outer atmosphere.

In testimony whereof I have hereunto set my hand at Chicago, Illinois, this 8th day of March, 1915.

EDWARD A. LARSON.
